UNITED STATES PATENT OFFICE.

EZRA S. BUCKNAM, OF PHILADELPHIA, PENNSYLVANIA, ASSIGNOR TO THE J. G. BRILL COMPANY, OF PHILADELPHIA, PENNSYLVANIA, A CORPORATION OF PENNSYLVANIA.

FARE-BOX.

1,032,876.

Specification of Letters Patent.

Patented July 16, 1912.

Application filed April 28, 1908. Serial No. 429,698.

To all whom it may concern:

Be it known that I, EZRA S. BUCKNAM, a citizen of the United States, residing in Philadelphia, Pennsylvania, have invented 5 certain Improvements in Fare-Boxes, of which the following is a specification.

My invention relates to certain improvements in fare boxes in which the fares inserted in the box pass into a removable receptacle which is taken from the box and opened to remove the contents.

My invention relates particularly to fare boxes used on what is termed "pay-as-you-enter" cars and the fare box in this instance 15 is secured to the platform of the car or other conveyance.

The object of my invention is to so construct the box that it will receive the fares collected by a number of conductors without 20 having to remove the receptacle when one conductor relieves another.

My invention relates further to other details of construction which will be described hereafter.

25 In the accompanying drawings:—Figure 1, is a perspective view of my improved fare box, with the receptacle detached; Fig. 2, is a detached perspective view of the receptacle; Fig. 3, is a vertical sectional view on the line 3—3, Fig. 4; Fig. 4, is a sectional view on the line 4—4, Fig. 3; Fig. 5, is a detached perspective view of the receptacle showing the door open and the drawer removed; Fig. 6, is a perspective view of the drawer; Fig. 7, is a sectional view on the line 7—7, Fig. 4; Fig. 8, is a sectional plan view on the line 8—8, Fig. 4; and Fig. 9, is a perspective view of the pivoted chute.

A is the body of the fare box, made as 40 clearly shown in Fig. 1, having a tapered portion a surmounted by a glazed fare receiving section a' . The body of the box is made of metal in the present instance, although it may be made of any suitable material without departing from the main features of my invention.

In the section a' is a series of deflecting plates a^2 and the lower deflecting or chopper plate a^3 is movable and operated by a lever 45 a^4 so as to allow the fares collected on the

plate to be discharged into the body of the box.

B is the receptacle in which is mounted a detachable drawer C and this drawer, as shown in Fig. 6, is divided by partitions into 55 four compartments c' , c^2 , c^3 , c^4 , and the mechanism is so constructed that the fares can be discharged into any one of the four compartments. The object of this construction is to allow the fares to accumulate in 60 the box for a day, for instance, and they need not be removed when one conductor is relieved by another.

The receptacle B has four slots b in its cover plate b' in the present instance and 65 these slots can be closed by a slide D mounted in ways on the underside of the cover plate, and may be operated in the manner set forth in my Patent No. 901,778, dated October 20th, 1908.

70 Within the tapered portion a and directly under the glazed section a' of the box is a funnel e , and under the funnel is a chute E pivoted at e , e to the casing A; the chute directs the fares into any one of the compartments c' , c^2 , c^3 , c^4 , according to the point at which it is set.

I preferably provide a slotted partition a^5 in the box directly above the receptacle; the slots in the partition being in line with the 80 slots in the receptacle. The end of the chute E is arranged so near the partition a^5 that the fares cannot escape from the chute into the space above the partition.

Attached to the chute E is an operating 85 knob E' which projects through a slot a^6 in the casing of the box A', and the walls of this slot are numbered 1 to 4, so that when the knob is opposite No. 1 on the slot, the end of the chute will direct the fare into the 90 compartment c' of the drawer and when it is opposite the other figures the end of the chute will direct the fare into the corresponding compartments.

In order to lock the chute in any one of 95 the four positions in which it is adjusted, I secure a segment E^2 to the chute, having a series of notches e^3 , Fig. 9, with which engages the bolt on a lock E^3 , so that when it is desired to shift the chute the key is in- 100

serted in the lock and the bolt withdrawn to free the chute, when it can be moved into any one of the four positions, or the teeth of the segment may be made inclined on one side, as in Fig. 9, and the bolt of the lock may be a spring bolt so that the chute can be moved forward a notch at a time but cannot be returned unless the bolt of the lock is withdrawn, therefore the chute can be set 10 at the beginning of the day in line with the first compartment c' and then moved forward one notch as one conductor takes the place of another.

The receptacle B, in order to provide for 15 the reception of the drawer C, is made in the following manner:—The mechanism for operating the slide D is contained within a compartment B' separated from the main portion B² by a partition b², as clearly 20 shown in Fig. 5, so that the drawer C can fill the compartment B² without interfering with the operating mechanism for the slide. The slide D is attached to the spindle f of the lock F by a link f' and levers f²; the 25 lever being loose on the shaft and the hub of the lever is slotted for the passage of the pin mounted on the spindle, so that there will be a certain amount of lost motion between the shaft and the spindle to allow 30 the slide to move first and close the slots before the bolt of the lock is retracted so that the receptacle can be removed from the box. The slide has a hooked extension d in the present instance, which can engage 35 the bolt g of the lock G on the door B³, Fig. 7, of the receptacle when the slide is moved to close the slots prior to the removal of the receptacle from the box. The mechanism for locking the box, the mechanism 40 for operating the slides and for locking the slides is fully set forth and claimed in the above mentioned patent.

The operation is as follows:—The car in making its first trip in the morning has the 45 chute E set to No. 1, and the end of the chute will be in line with the first compartment c' and all the fares received by the conductor making the run will pass into this one box, and when another conductor 50 replaces the first one he shifts the chute by taking hold of the knob and moving it to No. 2 position in line with the compartment c^2 of the drawer, then the fares of this conductor will pass into No. 2, and so on until 55 the end of the run for the day. The receptacle is then removed and taken to the depot and the drawer detached from the box and the car fares in each compartment of the drawer are counted separately. When the 60 drawer is removed from the receptacle another drawer is inserted in its stead or the contents of the first drawer can be quickly

emptied and the drawer replaced. In some instances, it may be desirable to have two sets of receptacles for each box so that as 65 soon as one receptacle is removed it can be instantly replaced by another. The chopper plate a³ is actuated in the present instance by a lever a⁴ pivoted at a⁷. One arm of the lever projects through a slot in the casing 70 A in easy reach of the conductor and the other arm of the lever is connected to a rod n adapted to guides, which rod is connected by a link n' to a plate n² secured to the chopper platform a³. This platform is preferably made of glass and is secured to the frame in any ordinary manner. A spring n³ attached at one end to the inner arm of the lever and to the casing tends to keep the chopper platform in its closed position. 80 When the tickets accumulate on the chopper platform, the conductor raises the lever a⁴ and allows the tickets to fall into the hopper e and they pass through the hopper to the proper compartment. 85

The glazed fare receiving section is fully set forth and claimed in an application for patent filed by myself and George B. Kohler, even date herewith, under Serial No. 429,738. 90

I claim:—

1. The combination in a fare box, of a body portion, a receptacle therein having a series of compartments, a pivoted chute adapted to aline with any one of said compartments, means for allowing the chute to move in one direction and means for preventing the chute moving in the opposite direction, and locking mechanism for controlling said last mentioned means, whereby on the operation of the lock the chute can be returned to its first position. 95

2. The combination in a fare box, of a body portion, a receptacle therein having a series of compartments, a pivoted chute adapted to aline with any one of said compartments, a toothed segment on the chute, and a lock so arranged as to engage the teeth of the segment and secure the chute in position. 105

3. The combination in a fare box, of a body portion, a receptacle therein having a series of compartments, a pivoted chute adapted to aline with any one of said compartments, a segment having teeth beveled on one side, a lock having a spring bolt adapted to engage the teeth so that the chute can be moved in one direction but will be prevented from moving in the opposite direction by the lock. 115

4. The combination in a fare box, of a body portion, a receptacle therein having a series of compartments, a pivoted chute adapted to aline with any one compartment, 120

a segment on the chute, a lock engaging the segment, an operating knob on the chute, the casing having a slot through which the knob extends, and stop marks on the walls of the slot coinciding with the compartments in the receptacle.

In testimony whereof, I have signed my

name to this specification, in the presence of two subscribing witnesses.

EZRA S. BUCKNAM.
